W. C. Shay,

INVENTOR

BY *Victor J. Evans,*

ATTORNEY

WITNESS:

UNITED STATES PATENT OFFICE.

WILLIAM C. SHAY, OF JAMESTOWN, NEW YORK.

TROUBLE LIGHT.

Application filed March 2, 1925. Serial No. 12,767.

To all whom it may concern:

Be it known that I, WILLIAM C. SHAY, a citizen of the United States, residing at Jamestown, in the county of Chautauqua and State of New York, have invented new and useful Improvements in Trouble Lights, of which the following is a specification.

This invention relates to improvements in trouble lights for use upon automobiles and the like and contemplates the provision of a novel form of holding means whereby the light may be readily and easily attached to any part of the vehicle in order that the light may be positioned at the desired point.

Another object of the invention is the provision of means included upon the outer side of the lamp casing whereby the same may be readily and easily attached to reflectors.

A further object of the invention is the provision of a multiple reflector which may have either one of its reflectors positioned upon the front of the lamp casing through the novel association with the holding means included upon the forward end portion of the lamp casing.

With the above and other objects in view, the invention further includes the following novel features and details of construction, to be hereinafter more fully described, illustrated in the accompanying drawings and pointed out in the appended claims.

In the drawing:—

Figure 1 is a side elevation of the present invention.

Figure 2 is a fragmentary longitudinal section showing the invention applied to an inclined surface.

Referring to the drawing in detail, where-in like characters of reference denote corresponding parts, the reference character 10 indicates a tubular casing member including a dielectric knurled knob 11 which is threadedly secured to the inner end 40 of the tubular casing 10 and includes an opening centrally thereof which receives suitable conducting wire 12 therethrough and into the lamp casing 10. The forward end portion of the lamp casing 10 is substantially enlarged as at 13 and includes at diametrically opposed points upon the outer sides thereof a pair of trunnion members 14. This enlarged portion 13 of the lamp casing 10 further includes a bayonet slot or the like, not shown, which is adapted to receive the socket por-

tion 15 of a lamp of the usual automobile incandescent type 16.

In order to provide reflecting means upon the forward end portion of the lamp casing 10 and which reflecting means may include the flared circumferential trouble light reflector or be reversed upon the forward end portion of the lamp casing 10 in order to provide a drop light and in order to accomplish this desired result and the peculiar construction of the above entitled invention, I provide a circumferential band 17 which includes outwardly extending longitudinal and transverse depressions 18 and 19, the reflecting means includes an outwardly extending flared reflector 20 and a substantially elliptical-shaped drop light reflector 21 thereon.

The special type of securing or holding means for the lamp casing as mentioned in the foregoing, includes a substantially Z-shaped supporting bracket 22 which has its upper end portion channeled or arcuate-shaped in order to snugly associate with the under side of the lamp casing 10 and has its lower end portion apertured and receiving a rivet or the like 23 therein which in turn is associated therewith a suction cup 24 which is preferably rubber and which when moistened and depressed upon a surface as shown in Figure 2 of the drawing, the same will stick owing to the vacuum formed by forcing all of the air of the space defined between the suction cup 24 and the surface to which it is applied and upon releasing the pressure exercised thereupon it will be noted, as is commonly known in the use of these suction cups, that the same will spring upwardly and firmly grip or adhere 90 to the surface to which it is applied, and owing to the simplicity and lightness of the above entitled invention which is applied to this suction cup 24, it will be noted that the said suction cup will adhere or stick 95 to a surface longer or at a longer period than would an article having more avoid-dupois.

A dielectric plug member 25 is secured within the lamp casing 10 by suitable fastening elements 26; this plug 25 includes spaced contact members 27 therein which are connected with the conducting wires 12 and have their opposite ends contacting with the contacts upon the end of the lamp socket 15.

In the use and operation of the present invention it will be clearly apparent that upon

the insertion of the flange member 17 on the outwardly flared portion 13 provided upon the forward end portion of the lamp casing 10, that the longitudinally extending 5 grooves 18 provided upon opposite sides of the flange member 17 may be readily and easily received on the trunnion members 14 provided at diametrically opposite sides upon the outer side of the outwardly flared 10 portion 13 on the outer end portion of the lamp casing 10 and upon a partial rotation of the flange 17 thereon, it will be noted that the trunnion member 14 will move transversely within the transversely extending 15 grooves 19 and be held against accidental displacement thereon. It will also be noted that upon reversing the flange member 17 on the outwardly flared portion 13 that the other reflector may be positioned over the 20 lamp 16.

The invention is susceptible of various changes in its form, proportions and minor details of construction, and the right is herein reserved to make such changes as properly fall within the scope of the appended 25 claims.

Having described my invention what is claimed is:

1. A trouble light, an incandescent lamp 30 included in the forward end portion, electric conducting means included in the opposite end portion thereof, attaching means included upon the lower side of the lamp casing, and a reversible reflecting means included upon the forward end portion of the lamp casing.

2. A trouble light of the character described comprising a substantially cylindrical longitudinally extending lamp casing, 40 the forward end portion of the lamp casing being substantially enlarged and including a pair of diametrically opposed outwardly extending trunnion members upon the outer sides thereof, an incandescent lamp bulb received in the outer end por-

tion within the enlarged portion of the lamp casing, a suction cup secured to the lower side of the lamp casing, and a reversible reflector arranged upon the outer side of the forward end portion of the lamp casing. 50

3. A trouble light of the character described comprising a substantially cylindrical lamp casing, the forward end portion of the lamp casing being substantially enlarged and including a pair of diametrically opposed trunnion members upon the outer sides thereof, bracket means included upon the lower side of the lamp casing, a suction cup secured to the lower end portion of the bracket means, and a multiple reflector having detachable connection with the outwardly flared portion of the lamp casing whereby the same may be readily and easily reversed upon the forward end portion of the lamp 60 casing. 65

4. A trouble light of the character described comprising a lamp casing having a substantially enlarged forward end portion, 70 said enlarged forward end portion including a pair of diametrically opposed outwardly extending trunnion members thereon, a dielectric cup member secured to the opposite end portion of the lamp casing and receiving suitable electric conducting means there-through, a substantially Z-shaped bracket secured to the lower side of the lamp casing, a suction cup secured to the lower end portion of the Z-shaped bracket, a flange member including longitudinal and transverse depressed portions pressed outwardly therefrom and adapted for selective engagement and locking association upon the outwardly flared portions with the trunnions thereon, and a pair of oppositely converging reflectors arranged upon opposite sides of the flange member. 75 80 85

In testimony whereof I affix my signature.

WILLIAM C. SHAY.
